UNITED STATES PATENT OFFICE.

GEORGE R. KING, OF NEW YORK, N. Y., ASSIGNOR TO J. B. KING AND COMPANY, A CORPORATION OF NEW YORK.

PLASTER-BOARD MACHINE.

1,033,251.

Specification of Letters Patent.

Patented July 23, 1912.

Application filed August 7, 1909. Serial No. 511,702.

To all whom it may concern:

Be it known that I, GEORGE R. KING, a citizen of the United States, and a resident of the city of New York, county of Richmond, State of New York, have invented certain new and useful Improvements in Plaster-Board Machines, of which the following is a specification.

The object of my invention is to make plaster board by machinery, either with or without the use of paper, and to make the same into proper lengths. This object is accomplished by my invention, one embodiment of which is hereinafter set forth.

For a more particular description of my invention, reference is to be had to the accompanying drawings, forming a part hereof, in which:

Figure 1 is a side elevation of one end of the machine. Fig. 2 is a side elevation of the other end of the machine. Fig. 3 is a longitudinal section of the machine with parts omitted. Fig. 4 is a sectional view taken on the line 4—4 of Fig. 3. Fig. 5 is a sectional view taken on the line 5—5 of Fig. 7 looking in the direction of the arrows. Fig. 6 is a longitudinal section of the paper roll supporting cones and also shows the shaft on which they are mounted. Fig. 7 is a plan view of the front half of the machine. Figs. 8 and 9 are rear and front end elevations showing details. Fig. 10 is an enlarged plan view showing the cutting and driving mechanism. Fig. 11 is an enlarged plan view of the saw carrying frame. Fig. 12 is a sectional view taken on the line 12—12 of Fig. 11, looking in the direction of the arrows. Figs. 13, 14, 15, 16 and 17 are detailed views showing the shifting mechanism for the carriage so that the saw will act only on the advance movement and not on the return movement. Figs. 18 and 19 are sectional views taken on the lines 18 and 19—19 of Fig. 16, looking in the direction of the arrows. Figs. 20 and 21 are a side elevation and plan view respectively, of the rear half of the machine.

Throughout the various views of the drawings, similar reference characters designate similar parts.

My improved plaster board machine 1 is provided with a suitable frame 2, made of

any suitable materials such as wood or iron, and this frame carries the mechanism of the machine which will now be described.

55

The machine is driven by a belt 3 or other suitable driving means, and this belt 3 runs on a pulley 4 fixed to a shaft 5 mounted in suitable bearings 6 secured to the frame work of the machine. An eccentric 7 is fixed 60 to said shaft 5 and engages a suitable strap 8 in the conventional manner and of the conventional kind, and this strap 8 is connected by connecting rod 9 to a lever 10 fulcrumed at 11 in any suitable manner and 65 near its upper end it is adjustably and pivotally connected to an adjustable link 12 which is similarly connected to a second lever 13 loosely mounted on a shaft 14 which is suitably journaled in supports 15 of the 70 frame 2 of the machine. The lever 13 carries a suitable pawl 16 which engages a suitable ratchet wheel 17 fixed on the shaft 14 so that the oscillation of the lever 13 on the shaft 14 drives the shaft 14 in one direction 75 dependent upon the positions of the pivots on each end of the link 12 on the levers 10 and 13.

The rod 9 and the rod 12 shift the ratchet wheel 17 only when moved from left to 80 right when in the position shown in Fig. 10, that is, only when said rods are in tension. The ratchet wheel 17 drives the shaft 14 to which it is fixed, and the shaft 14 carries a gear wheel 18 which is fixedly mounted 85 therein and drives a pinion 19 fixedly mounted on a shaft 20 and journaled in suitable bearings 21 supported by the frame work 2 of the machine.

The shaft 20 carries a drum 22 on which 90 is the main carrying belt 23 of the machine. This belt 23 carries thickened edges 24 which are so arranged and disposed as to make a border for the belt 23 equal in thickness to the thickness of the finished plaster 95 board and the belt 25 which rests on the belt 23. This belt 25 is made a little longer than the belt 23 and runs over an idle pulley 26 suitably mounted in the frame work of the machine and so arranged and disposed as 100 to carry the plaster board 27 for a short distance after the same has been forced away from the belt 23 and its thickened edges 24. The belt 23 is also supported at its forward

end by a second drum 28 fixedly mounted on a suitable shaft 29 which is carried in suitable bearings mounted on the frame work of the machine. The shaft 29 also carries a sprocket wheel 30 on which is a sprocket chain 31 that drives a second sprocket wheel 32 fixedly mounted on a shaft 33 carried in suitable bearings secured to the frame 2.

The shaft 33 carries a brush 34 which 10 rubs against the belt 25 on its lower and inoperative run from the rear to the front of the machine and cleans the same. This brush is driven in the opposite direction from the direction of movement of the belt 25 so that it gives the same a thorough cleaning and removes any plaster which may have come from the board 27.

Immediately under the pulley 28 is a tank or trough 35 which is provided with oil and 20 in this oil runs a suitable brush or other conveyer 36 which is made in cylindrical form and suitably mounted on a shaft 37 journaled in suitable bearings 38 connected to the frame of the machine and this brush or lubricator 36 rubs against the belt 25 and lubricates the same so that the plaster board 27 will not stick thereto when the machine is in operation. The upper and operative run of the belts 23 and 25 is over 25 a table 39 supported by the frame 2 and this table 39 is interrupted with suitable rests in which are placed rollers 40 journaled in suitable bearings 41 so as to support the said belts from place to place and 30 also to form supports for the belt under calendering rolls hereinafter described.

Above the roll 28 is an idle roller 42 which rests on the belt 25 and presses the same firmly against the belt 23 and also distributes the lubricant if such a distribution is necessary. Immediately after leaving the roller 42 the belt 25 comes under a suitable source of plaster supply 43 which may be of any suitable kind or form and is preferably 45 substantially like that shown in my co-pending application filed the 16th day of November, 1908, Serial Number 462,808 which places on said belt the material necessary for the plaster board. Immediately after 50 leaving this source of supply the belts 23 and 25 pass under a roller 44 mounted on a suitable shaft 45 and journaled in suitable bearings 46 secured to the frame 2 of the machine. In Fig. 3 a paper roll 47 is shown 55 mounted on suitable cones 48 on a shaft 49. This paper roll is to be used when the plaster board is to have paper attached on one side and may be omitted if desired and then the board will be made without 60 paper. The shaft 49 is provided with a pulley 50 over which passes the usual weight and band to act as a brake to prevent the roll from turning too freely.

In the preferred embodiment of my invention the roller 44 is at one end of a belt

51 which is inoperative on its upper run and on its lower run is parallel to the belts 25 and 23 so that the plaster board when formed is formed between belts which protect the board from any deleterious influence from the rolls while the plaster is setting. The lower run is the operative run of the belt 51 and this belt is made of such a width that it fits between the thickened edges 24 of the belt 23, that is, it is the same width as the belt 25. On its upper run the belt 51 may be supported by idle rollers 52 mounted in suitable bearings 53 on the frame 2 of the machine. The lower and inoperative run of the belts 23 and 25 are also supported by similar rollers 52 mounted in suitable bearings and brackets 53. From the roller 44 the belt 51 passes on under a series of heating or calendering rolls 54. The purpose of these calendering rolls 54 is to give proper shape, density and thickness to the plaster board 27 in conjunction with the rolls 40 and also to heat the plaster so as to cause a quick setting of the plaster so that it will be sufficiently firm and set when it passes from the machine so as to permit of proper handling.

As the rolls 54 are identical, a description of one will answer for all. Each roll 54 is supplied with steam from a pipe 55 through T's 56, stud pipes 57 and packing boxes 58. The pipes 57 pass into the interior of the hollow rolls 54 and admit steam thereto. An exhaust pipe 59 has T's 60 and stud pipes 61 passing through packing boxes 62 into the interior of the hollow rolls 54 and each stud pipe 61 is bent at its lower end so as to trap the steam above the water of condensation, as shown in Fig. 5. By means of the steam passing through them, the rolls 54 are kept at any desired temperature. Each roll 54 is journaled in suitable bearings 63 which are well lubricated because of the steam heat.

The bearings near the stuffing boxes 58 are separated from the stuffing boxes by a sufficient distance to allow sprocket wheels 64 to be placed thereon, which sprocket wheels carry sprocket chains 65 arranged and disposed as shown so that one positively drives another at precisely the same speed and the first roll 54 is driven by a chain 66 that runs from a sprocket wheel 67 on the shaft 45 of the roll 44. A second sprocket 68 near the sprocket 67 and fixed to the same shaft is driven by a chain 69 that runs from a sprocket 70 which is fixed to a gear 71 on a shaft 72, and this gear 71 meshes with gear 73 on the shaft 29 which is driven by the main belt 23 by means of the drum 28. From the calendering rolls 54 the belt 51 passes to idle rollers 74, 75 and 76 mounted in suitable bearings on a bracket 77 secured to the frame 2 of the machine and thence over a cleaning brush 78 in suitable

bearings 79 on the frame 2 and similar in all respects to the cleaning brush 34, above described. This brush 78 is driven by a suitable sprocket chain 80 and sprocket 5 wheels 81, one of these being on the shaft 79 and the other on the shaft 20. After passing over the cleaning brush 78 which is driven in the same direction as the movement of the belt, the belt 51 passes over a lubricating roller or brush 82, similar in all respects to the brush 36 and mounted on a shaft 83 running in suitable bearings 84 and the brush 82 dips into a suitable trough 85 carrying the lubricating material. The belt 10 51 is lubricated where it passes over a roller 86 mounted in suitable bearings 87 supported on the frame 2 of the machine so that the belt 51 is first cleaned and then lubricated at the rear of the machine and then 15 run to the front end of the machine in its cleaned and lubricated condition, and then passed over the roller 44 and on top of the paper and plaster board, if paper is employed, and if paper is not employed, immediately 20 on top of the plaster board.

The lever 10 which is oscillated as above described, in addition to driving the machine drives the saw mechanism which is so arranged and disposed that on the stroke from 25 front to rear and while the pawl 16 is passing over the ratchet teeth of the ratchet 17 and so not running the belts and rollers above described, so that the plaster board is momentarily stationary, the mechanism described below causes a saw to cut through the board 27 whereby the plaster board is severed into appropriate lengths. The mechanism by which this is accomplished will now be described. A link 88 is pivotally connected 30 to the lever 10 and at its other end is connected to a cross head 89 which slides in suitable guides 90 fixed in an extension of the frame 2 and the cross head 89 is enlarged near its center and provided with a 35 transverse slot 91 in which runs a pin 92 fixed to the shorter arm of a bell crank lever 93 suitably pivoted at 94 so as to oscillate in a horizontal plane. The longer arm of the bell crank lever 93 is pivotally connected 40 to a link 94^a which at its other end is pivotally connected to a cross head 95 that carries an electric motor 96 on which is a circular saw that is adapted to rotate to saw the plaster board, as above described. The 45 electrical connections for the motor are omitted as they are obvious. When the machine is in operation the motor runs continuously. The cross head 95 moves in suitable guides 98 and 99 in each of which is provided upper and lower parallel grooves 100 and 101 and suitable switches 102 and 103 which are so arranged and disposed that on the stroke for cutting, which I will call the advance stroke, the cross head 95 50 travels in the grooves 100 and on the return

stroke, that is, the inoperative stroke, this cross head travels in grooves 101. The switches 102 and 103 may be either simple switches actuated by gravity as shown in Fig. 16 or they may be more complex and controlled by the movement of the cross head 95 and its attached parts, as well as gravity, if so desired. In the construction shown in Fig. 12 the switch 102 is gravity-controlled and is pivoted at 104 so that on its return movement the cross head 95 simply raises the same and passes under and continues moving until it strikes a lever 105 fulcrumed at 106 and at its lower end pivotally connected to a link 107 which runs to 70 a corresponding lever 108 at its other end and to which it is pivotally connected, which lever 108 is pivoted at 109 and provided with a head 110 against which the cross head impinges when moving in the 75 direction of this lever.

The link 107 carries a pin 111 which enters the slot in the arm 112 which is fixed to and projects from a shaft 113 mounted in suitable bearings 114. The shaft 113 also carries a counter-weight arm 115 which is fixed thereto and the free end of this arm 115 carries a suitable weight 116 which acts as a counterbalance for the switch 103. The switch 103 has a depending arm 117 on each 90 side and each arm is connected to an arm 118 fixed on the shaft 113 by sliding pivotal connection so that when the arm 112 is shifted from right to left as in Fig. 12, the switch 103 is raised. When the arm 112 is 95 lowered. This moving of the switch 103 is accomplished through the levers 105 and 108, the lever 105 raises the switch 103 and the lever 108 lowers the same and these 100 levers rock when moved by the cross head 95. In the structure shown in Fig. 16, the same result is obtained with less mechanism. There the switch 102 acts the same as before but the switch 103 consists of nothing but a 105 tongue 119 fixed to a short stud shaft 121 journaled in the frames 98 and 99 to which a weighted lever 120 is also secured so that 110 said tongue 103 is always maintained in this elevated position unless forced down by the 115 cross head. The cross head 95 is provided with a bottom 122 which has projecting lugs or pintles 123 that take into the grooves 100 or 101. The bottom 122 also carries suitable bolts 124 which support the top 125 120 at any desired elevation that the adjustment of the machine may require, and to this top 125 is bolted the motor 96 which carries the saw 97. The link 94^a is connected to the cross head 95 by means of a suitable bracket 125 126 through which passes a pin 127 and the bracket 126 is preferably secured to the bottom 122 in any suitable manner. Above the plaster board and at each side of the saw 130 are the parallel straps 128 between which

the saw passes on its operative movement and below which and below the plaster board it passes on its inoperative movement. The object of these two parallel straps is to prevent the saw from injuring the plaster board while cutting the same.

The operation of my improved machine will be readily understood from the foregoing. When the machine is operated, power is applied through the pulley 4 by the belt 3 in the conventional manner. The eccentric 7 acting through the rod 9 gives the lever 10 an oscillating movement and this lever in turn oscillates the lever 13 and causes the same to oscillate on the shaft 14. The oscillation of the lever 13 through the pawl 16 turns the ratchet in a clockwise direction thereby turning the shaft 14 on which the gear 18 is fixedly mounted which gear drives the pinion 19 and shaft 20 and the drum 22 fixed thereon and this drum drives the belt 23 and the drum 28 and through the mechanical connections the upper belt 51 and the calendering rollers 54. The cleaning and lubricating brushes for both the upper and lower belts are also driven as above described and the saw mechanism is also synchronously actuated so as to sever the plaster board into appropriate lengths. The plaster is put on the belt 25 by the device 43 or otherwise, between the rollers 42 and 44 and thence passes under the paper from the roll 47, if such paper be employed, and is spread out on the belt 25 between the borders 24 and after leaving the roller 44 is spread under belt 51 if such a belt be employed, either with or without the paper, and thence passes under the hot calendering rolls 54, so that the plaster is properly dried and set, so that when it reaches the rollers 75 and 26 which draw the belts away and pass the plaster board on to the sawing mechanism where it is severed into proper lengths and then may be removed from the machine in any desired manner. The plaster board is not continuously fed but intermittently with periods of rest during which the saw severs the board as above described.

In view of the foregoing, it is obvious that I have shown and described a machine which is automatic in its operation and capable of manufacturing plaster board without any manual operation whatsoever.

While I have shown and described one embodiment of my invention, it is obvious that it is not restricted thereto, but is broad enough to cover all structures that come within the scope of the annexed claims.

Having thus described my invention, I claim:

1. In a machine of the class described, means for receiving plaster, means for spreading the same, heating means beneath which the same passes, causing the plaster

to set quickly, and means for severing the plaster board into appropriate lengths.

2. In a machine of the class described, means for receiving plaster, means for distributing the same, means for moving the plaster through the machine with an intermittent motion, heating means under which said moving means passes to cause the plaster to set quickly and means for severing the plaster board into predetermined lengths during its periods of rest.

3. In a machine of the class described, means for receiving plaster, means for distributing the same, revoluble means for pressing and drying the plaster board, and means for severing the board into appropriate lengths.

4. In a machine of the class described, a pair of belts for receiving plaster, one resting on the other, and one of said belts provided with flanges between which the other rests, rollers for distributing said plaster, and rollers for heating and setting the same.

5. In a machine of the class described, a frame and drums mounted so as to rotate in said frame, means for rotating one of said drums intermittently, belts mounted on said drums, the first belts having flanges on its edges and the second belt resting on the first and between said flanges, and means cooperating with said belts for heating and distributing plaster between said flanges and on said belts.

6. In a machine of the class described, a frame and drums mounted to rotate therein, means for moving plaster through the machine, means for rotating one of said drums intermittently, means for cleaning the plaster moving means, means for heating the plaster during a portion of its movement through the machine and independent rotary means for lubricating the plaster moving means.

7. In a machine of the class described, a frame, a pair of parallel drums mounted in said frame, means for driving said drums intermittently, belts carried by said drums, an upper belt above said drums, and means for mounting the same, means for forming a plaster board between said upper and lower belts, and calendering means for causing the plaster to set quickly and means for supplying a heating medium to the calendering means.

8. In a machine of the character described, a frame, an upper belt mounted in said frame, idle pulleys carrying said belt, calendering means, means for heating the same to cause the plaster to set quickly, means for cleaning said upper belt and rotary means acting on the under side of said belt to lubricate the same.

9. In a machine of the class described, a set of calendering rolls, each of which is provided with means for admitting steam,

- and means for permitting the water of condensation to escape, a belt movable beneath said rolls and means for supplying plaster to said belt.
- 5 10. In a machine of the class described, a frame, a pair of parallel drums mounted in said frame, belts mounted on said drum and means for driving one of said drums intermittently, an upper belt and means for 70 mounting the same, means for driving said upper belt from one of said drums, a series of calendering rolls and means for heating the same, and means for driving the same.
11. In a machine of the class described, 15 parallel guides with upper and lower tracks, vertically movable switches at each end of said tracks, and a cross-head moving in one direction in one of said tracks and the other direction in the other of said tracks.
- 20 12. In a machine of the class described, means for forming plaster board guides with upper and lower tracks therein, switches at each end of said tracks, a cross-head adapted to move in one direction in one 80 set of tracks and in the other direction in the other set of tracks, and cutting mechanism carried by said cross-head adapted to sever said plaster board during its period of rest.
- 25 13. In a machine of the class described, an oscillating lever and means for driving the same, a cross-head 89, a link connecting said cross-head and oscillating lever, guides for said cross-head and a bell-crank lever 85 connected to said cross-head and means for supporting the same, a second cross-head and means for mounting the same, cutting mechanism carried by said last mentioned cross-head, and a link connecting said last mentioned cross-head with said bell-crank lever.
- 30 14. In a machine of the class described, means for receiving plaster, means for spreading the same, and rotary heating 90 means for causing the plaster to set quickly.
- 35 15. In a machine of the class described, a plurality of simultaneously movable belts one within the other, one of which is longer than the other, and heating means for causing plaster carried by said belts to set quickly.
- 40 16. In a machine of the class described, a plurality of simultaneously movable belts one within the other and resting thereon, one of which is longer than the other, and heating means for causing plaster carried by said belts to set quickly.
- 45 17. In a machine of the class described, a plurality of simultaneously movable belts one within the other and one resting upon the other and one provided with thickened edges, and heating means for causing plaster carried by said belts to set quickly.
- 50 18. In a machine of the class described, a belt having a thickened edge, and the belt of 95
- less width mounted above and around and for a coöperative movement simultaneously with the first-named belt, and heating means for causing plaster carried by said belts to set quickly.
19. In a machine of the class described, a belt having a thickened edge, and the belt of less width mounted above and around and for a coöperative movement simultaneously with the first-named belt, of greater 75 width, and heating means for causing plaster carried by said belts to set quickly.
20. In a machine of the class described, a belt having a thickened edge, and a belt of less width mounted above and around and for a coöperative movement simultaneously with the first named belt of greater width and a protecting belt for the same, and heating means for causing plaster carried by 80 said belts to set quickly.
21. In a machine of the class described, a plurality of belts one within the other and one of which is shorter than the others, two of which on their operative runs are in close proximity to each other, and the other one 90 of which on its operative run is slightly above the uppermost thereof, and heating means for causing plaster carried by said belts to set quickly.
22. In a machine of the class described, a plurality of belts one within the other and none of which, on their operative runs, moves in contact with the others, one of said belts having thickened edges, and a protecting belt which on its operative run moves 100 over the uppermost of said belts and heating means for causing plaster carried by said belts to set quickly.
23. In a machine of the class described, a plurality of belts one within the other and one upon the other for moving plaster, and a supplemental belt above the same with means for cleaning the same, and heating means for causing plaster carried by said belts to set quickly.
24. In a machine of the class described, a plurality of belts one within the other and one upon the other for moving plaster, and a supplemental belt above the same with rotary means for lubricating the under side 115 of the same, and heating means for causing plaster carried by said belts to set quickly.
25. In a machine of the class described, a pair of receiving belts one within the other and one resting on the other and one provided with thickened edges, and means for heating the plaster distributed on said belts.
26. In a machine of the class described, means for receiving plaster, means for moving the same with an intermittent motion, 120 heated rotary means for causing the plaster to set quickly, a reciprocating saw carrier and means for actuating the same during the periods of rest of said means.
27. In a machine of the class described, 130

means for receiving plaster, means for moving the same with an intermittent motion, means for severing the plaster board during the periods of rest of said means, means for reciprocating the same, a movable carrier therefor, and means constructed to automatically switch the carrier at each end of its stroke.

28. In a machine of the class described, means for receiving plaster, means for moving the same with an intermittent motion, means for severing the plaster board during the periods of rest of said means, a movable carrier for said severing means, guides for said carrier, and means for automatically switching the carrier at each end of its stroke from one set of guides to the other.

29. In a machine of the class described, means for receiving plaster, means for moving the same with an intermittent motion, heated rotary means for drying the plaster, means for severing the plaster board during its periods of rest, and means for reciprocating said severing means and reversing its motion at each end of its stroke.

30. In a machine of the class described, an endless belt, heating means for causing plaster carried by said belt to set quickly, and rotary means for lubricating the under side of said belt upon its inoperative run.

31. In a machine of the class described, an endless plaster-carrying belt, heating means for causing plaster carried by said belt to set quickly, and rotary means for

cleaning the under side of said belt upon its inoperative run.

32. In a machine of the class described, an endless plaster-carrying belt, rotary means for cleaning the under side of the same, means for lubricating the under side of said belt upon its inoperative run and heating means for causing plaster carried by said belt to set quickly.

33. In a machine of the class described, a set of calendering rolls, means for heating the same, means for permitting the water of condensation to escape and means for trapping the steam above the water of condensation.

34. In a machine of the class described, belt-actuating means, a board-severing device operatively connected therewith, a carrier and means constructed to automatically switch the same at each end of its stroke.

35. In a machine of the class described, belt-actuating means, a board-severing device operatively connected therewith, a carrier for said device, means for automatically switching the same at each end of its stroke and a motor carried by the carrier of said severing device.

Signed at the city of New York, county of Richmond, State of New York, this 5th day of July, 1909.

GEO. R. KING.
